UNITED STATES PATENT OFFICE.

GEORGE H. SALTSGIVER AND JOHN H. BURKE, OF SIOUX, NEBRASKA.

GRAIN-DOOR FOR FREIGHT-CARS.

1,123,387.

Specification of Letters Patent.

Patented Jan. 5, 1915.

Application filed October 21, 1913. Serial No. 796,462.

To all whom it may concern:

Be it known that we, GEORGE H. SALTSGIVER and JOHN H. BURKE, both citizens of the United States, and residents of the city of Sioux, in the county of Dakota and State of Nebraska, have invented certain new and useful Improvements in Grain-Doors for Freight-Cars, of which the following is a specification.

10 This invention relates to grain-doors for freight cars.

The invention has for its primary object the construction of an improved door for freight cars employed in the transportation of grain or other materials which are of like nature and usually loaded in bulk.

15 Another object of the invention is the construction of a device of this class which may be easily raised and swung laterally, yet which is thoroughly efficient and secure in closed position.

20 A further object is the provision in a device of this class of improved operating means requiring the application of comparatively little power.

25 A still further object of the invention is the construction of a grain door which is inexpensive in both manufacture and maintenance yet stable and durable.

30 With these and other objects in view, the invention, consisting in the construction, combination and novel arrangement of parts, will be fully understood from the following description, reference being had 35 to the accompanying drawings which form a part of this application and in which like characters of reference indicate corresponding parts throughout the several views, of which—

40 Figure 1 is an inside elevation of a device constructed in accordance with our invention; Fig. 2 is a plan view of the same, the supporting shaft being shown in section; Fig. 3 is a fragmentary elevation of the door as viewed from the outer side; Fig. 4 is a vertical section of the supporting shaft and members associated therewith; Fig. 5 is a side elevation of the bracket; Fig. 6 is an inverted plan view of ratchet mechanism which may be substituted for the crank-operating means; Fig. 7 is a side elevation of the same attached to the sill of a car; and Fig. 8 is a longitudinal section of a car with the device of our invention 55 mounted therein.

The invention contemplates, broadly, a

door which normally embraces the door-frame and is supported by brackets which are threaded upon a vertically-disposed shaft rotatably-mounted within the car 60 whereby the door may be swung laterally upon, or moved longitudinally of the shaft by rotation of the latter, all of which will presently be made clear.

Although we have illustrated and herein 65 described an embodiment suitable for practicing the invention, we would not be understood as being limited to the specific structure selected for illustration, for, without departing from the spirit and scope of 70 the invention, various modifications and alterations may be made in the construction and arrangement of the several parts.

Referring now to the illustrations, the door, 11, preferably constructed of sheet- 75 metal, is suitably secured at one edge, as by rivets, 12, to an upright bar, 13, the ends of which are bent at right-angles and form horizontal arms, 14, which inclose a shaft, 15, which has threaded engagement with the upper arm, 14, and is journaled in suitable bearings, 16 and 17, mounted in the ceiling and floor of the car, 18 and 19, respectively.

Intermediate the lower bracket member, 85 14, and the bearing, 17, the shaft is provided with a stop, 20, which serves to prevent downward displacement of the shaft.

The lower bearing may extend below the car body if desired and be provided with a transverse bore, 21, adapted to register with a similar bore, 22, in the shaft, for admission of a seal, 23, commonly used upon car-doors, and which will prevent rotation of the shaft.

95 The lower end of the shaft is provided with suitable means for imparting rotation thereto, which means may be a crank, as 24; or, in order to lessen the power required, a pinion, 25, may be mounted upon the lower end of the shaft, which is engaged by spur-gear, 26, rotatably-mounted upon a bolt, 27, secured by a nut, 28, within a flanged bushing, 29, secured by screws, 30, within the floor of the car. Upon the bolt, 27, is fulcrumed a lever, 31, equipped with a double pawl, 32, which is pivotally-secured at its center to the lever. A torsion spring, 33, one end of which is secured to the outer edge of the pawl at a point equidistant from either toe thereof; and the opposite end of which is secured to the lever at a point

aligned with the pivot of the pawl and the axis of the spur-gear, serves to maintain either toe of the pawl in engagement with the spur-wheel. It is now clear that upon 5 vibratory movement of the lever, the pawl and gears will coact in rotating the shaft, 15, whereby the door will be raised or lowered, according as which toe of the pawl is engaged.

- 10 In order to relieve somewhat the pressure of the car's contents against the door, and thus facilitate the raising of the door, a small opening, as at 34, may be provided in the door, which opening is normally-closed
- 15 by a suitable door, 35, slidably secured adjacent the outer side of the door proper; and through which opening a portion of the contents may be permitted to escape prior to raising the door.
- 20 As some structures with which the device of our invention are loaded over half full, we provide an extension 36, which is hingedly-secured to the upper edge of the door, and, when not supported by the car's
- 25 contents, will swing downwardly and inwardly, whereby the door may be raised sufficiently to clear the load when swung into the position indicated in dotted lines in Fig. 8.
- 30 The great majority of grain-doors familiar in the prior art, are supported in open position from the roofs of the cars. Obviously, the operation of such devices is

difficult and requires the presence of the operator within the car. Furthermore, 35 many serious accidents have occurred due to the doors being accidentally released from their supports.

Not alone does the superiority of the present invention reside in the removal of the 40 defects recited above, but also in the simplicity, durability and inexpensiveness of manufacture.

Having thus described our invention, what we claim as new and desire to secure by Let- 45 ters Patent of the United States, is,—

The combination with a car having a doorway therein and a door to normally embrace the inner side thereof, of an upright shaft rotatably mounted at one side thereof and 50 threaded a portion of its length, said door having arms inclosing said shaft, one of said arms engaging the threaded portion of said shaft, and means for rotating said shaft whereby the door may be raised and lowered 55 and swung laterally when the latter arm reaches the end of the threaded portion.

In testimony whereof we have hereunto set our hands this 10th day of October, 1913, in presence of two witnesses.

GEORGE H. SALTSGIVER.
JOHN H. BURKE.
